SAIL CAR

Leon M. Levy, 2023 N. Dayton St.,
Chicago, Ill. 60614

Filed Dec. 11, 1968, Ser. No. 14,893

Term of patent 7 years

Int. Cl. D12—13

U.S. Cl. D14—3

FIG. 1 is a perspective view of a sail car showing my design, and

FIG. 2 is a top plan view taken on line 2—2 of FIG. 1. The dominant features of my design reside in the portions shown in full lines.

I claim:

The ornamental design for a sail car, as shown and described.
